UNITED STATES PATENT OFFICE.

ALBERT FRANK WESTLUND, OF INDIANAPOLIS, INDIANA, ASSIGNOR TO PREST-O-LITE CO., INC., A CORPORATION OF NEW YORK.

CYLINDER-FILLING MACHINE.

1,366,615.

Specification of Letters Patent. Patented Jan. 25, 1921.

Application filed August 30, 1919, Serial No. 320,851. Renewed December 14, 1920. Serial No. 430,746.

To all whom it may concern:

Be it known that I, ALBERT FRANK WESTLUND, a citizen of the United States, residing at Indianapolis, in the county of Marion and State of Indiana, have invented certain new and useful Improvements in Cylinder-Filling Machines, of which the following is a full, clear, and exact description.

At the present time the storage of compressed, dissolved, acetylene, for its various industrial uses, is effected in steel or other suitable metal containers filled with a porous substance, into which a proper quantity of a suitable solvent for acetylene, such as acetone, is added, which solvent readily takes up the proper proportion of gas charged into the cylinder under pressure.

Practical considerations, in some cases, demand that the steel or other metal container, have only a small orifice, at the time the porous substance is filled into the cylinder, through which orifice the porous substance must be added, which porous substance, at the time of filling into the cylinder, is of such a nature that it will not flow through the small orifice.

A porous substance commonly employed for filling into cylinders, which have a small filling orifice, often consists of a wet, sticky, gritty, or heterogeneous substance preferably composed, in the main, or essentially, of a wet mixture of small pieces of charcoal and kieselguhr, together with cement or such other materials as are now known or used for the purpose.

The problem of filling the containers with this or an equivalent substance is by no means a simple one nor easy of accomplishment, but I have devised an apparatus for the purpose which fully meets all of the exacting demands of such an operation. This apparatus generally stated comprises a hopper with a contracted outlet overlying the orifice of a container, and provided with a reciprocating plunger, and a plurality of rotating and reciprocating tampers which force the substance down under the plunger enabling the operation of the latter to force it down through the orifice into the container.

Suitably constructed means may be employed for automatically effecting the necessary operations of the plunger and the tampers, and means may also be employed for jarring the container so as to cause the

injected substance to properly settle and completely fill its interior.

This apparatus is the subject of my present application for Letters Patent. I have illustrated it in its preferred form in the accompanying drawings, in which—

Figure 1 is a side view in elevation of the complete apparatus.

Fig. 2 is a similar view of the same but from another side.

Fig. 3 is an enlarged detail of the filling mechanism, the hopper being shown in section, and

Fig. 4 is a similar view of the same parts, but in a different operative position.

Similar reference numerals indicate corresponding parts in the several figures.

Except in so far as may be particularly pointed out herein, the specific construction of the parts or elements comprised in my apparatus are not of the essence of my invention. With this understanding it may be described as comprising a suitable supporting frame 1, having a horizontal support 2 for a funnel shaped hopper 3. The frame 1 has, preferably, a movable bottom 4, for the container 5, the orifice 6 of which is immediately under the end of the contracted outlet 7 of the hopper 3.

In the upper part of the frame 1 is mounted a drive shaft 8 having a pulley 9, a crank 10, and a beveled pinion 11. The crank reciprocates a plunger 12 through the cylindrical and contracted outlet 7.

To a sleeve 13 rotatably mounted on the plunger 12 is fixed a horizontal arm 14, to the opposite ends of which are pivoted the top members of double levers 15, 15, the lower members of which constitute tampers working in the lower part of the hopper 3 and having a reciprocating motion imparted to them by their connection with the plunger. The upper members 15 are pivoted at 16 to arms 17 secured to a large gear wheel 18 engaged and rotated by a pinion 19 in gear with the shaft 8, and hence have a movement the exact converse of that of the plunger. As the latter rises, therefore the tampers force the material down to the bottom of the hopper when it will be met by the plunger and forced out of the hopper and into the container.

The arms 17 are extended down below the pivotal points 16 and have bifurcated ends which engage the lower members 15, and by 110

means of these arms a constant rotary motion is imparted to the tampers.

To the lower part of the frame on each side are secured brackets 19 affording bearings for a shaft 20 having rigid crank arms 21. One of these arms is connected by a link 22 with the short arm of a crank pivoted, at 23, the other arm of which is a handle or lever 24. By the operation of this lever the shaft 20 is oscillated and by this means a jolting or jarring movement is imparted to the bottom 4 by means of connecting links 25, and as the container is being filled it is jolted or jarred by the means described, whereby its contents are settled in a more compact and evenly distributed mass.

The above described elements comprise the main and essential parts of my improved apparatus, and no more detailed description of their operation or mode of use, is required, as these will be readily understood by those skilled in this art. The same is true of the subsequent treatment or preparation of the filled containers, as these differ in no essential respect from those heretofore practised in the art. Manifestly, the filling machine may be applied to various purposes besides the one specifically mentioned.

30 What I claim as my invention is:

1. In a device of the kind herein described, the combination with a suitable

supporting frame, of a hopper for containing the filling substance, and having a contracted outlet at the bottom, a reciprocating plunger therein for forcing the substance out through the outlet and a plurality of rotating and reciprocating tampers adapted to force the material toward the outlet and under the plunger.

2. In a device of the kind herein described, the combination with a suitable supporting frame of a hopper for containing the filling material, a reciprocating plunger for forcing the material out through an outlet in the hopper, a series of tampers co-operating with the plunger to force the substance under the same, and means for reciprocating the plunger and tampers and rotating the latter at the same time.

3. In a device of the kind herein described, the combination with a suitable frame of a hopper for containing the filling substance, a plunger for forcing said substance out through an outlet, means for reciprocating the plunger, a plurality of tampers connected with and adapted to be reciprocated by the plunger, and gearing between the reciprocating means and said tampers whereby the latter are continuously rotated while reciprocating.

In testimony whereof I have hereunto affixed my signature.

ALBERT FRANK WESTLUND.
